UNITED STATES PATENT OFFICE.

SUMNER F. CALL, OF HARTFORD, CONNECTICUT.

WATERMELON CARRIER.

Application filed October 22, 1921. Serial No. 509,543.

To all whom it may concern:

Be it known that SUMNER F. CALL, a citizen of the United States, residing at Hartford, in the county of Hartford and State 5 of Connecticut, has invented certain new and useful Improvements in Watermelon Carriers, of which the following is a specification.

This invention relates to a watermelon-10 carrier. I use the term more or less for convenience, and for the further fact that the article has been found of particular advantage for supporting and transporting a watermelon. It is conceivable that said device 15 can be utilized with equal advantage in connection with other fruits, such as casaba melons, cantaloupes and fruit of the same general character, although it is of peculiar importance when employed for carrying a watermelon. While I have a 20 number of objects in view, the more important of them, are the provision of means of a proper nature which can be readily, and practically instantly operatively associated 25 with a fruit, such as a watermelon, and by which the fruit can be carried in a satisfactory manner without possibility of loss. It is a matter of fact that on the purchase 30 of a watermelon, the purchaser ordinarily has it sent home by truck or otherwise. I provide a device which can be quickly connected with a watermelon, and by which it can be easily carried.

In the drawings accompanying and forming 35 part of the present specification I have shown in detail a form of embodiment of the invention which to enable those skilled in the art to practice the same will be set forth fully in the following description. Obviously 40 I am not restricted to the exact disclosure thus made. I may depart therefrom in a number of respects within the scope of the invention defined by the claim following said description.

45 Referring to said drawings:—

Figure 1 is a top plan view of a watermelon-carrier involving the invention.

Fig. 2 is a side elevation and

Fig. 3 an end view of the same.

50 Fig. 4 is a top plan view of a strap.

Fig. 5 is an edge view of the same.

Fig. 6 is a side elevation of a handle.

Figs. 7 and 8 are end and top plan views 55 of the handle.

Fig. 9 is a view on a small scale showing a manner of using the article.

The device includes in its structure desirably two straps which may be of any suitable material. The elongated straps 2, of which there are two generally in practice 60 and of some galvanized sheet metal answers satisfactorily in this connection. The straps 2 are furnished with some suitable means for their positive connection with a watermelon or like fruit, and the spurs 3 which 65 may be punched from the stock of the straps or strips 2 answers satisfactorily in this connection. Obviously there may be any number of these spurs. In some cases there may be but one; as a matter of fact it may 70 not always be necessary to provide spurs for positively connecting the straps or strips with the melons. When the straps are connected to the article to be carried, the spurs 3 are thrust into the melon and are then 75 wrapped transversely about the same at longitudinally separated places as shown for instance in Fig. 9.

Associated with the straps or strips 2 is a suitable handle such as that denoted in a 80 general way by 4 and which will herein-after be more fully described. One end portion of each of the straps 2 has as shown a single hole or perforation as 5 although if desired a number may be formed therein. 85 The other end portion of the respective straps has a row of holes 6 so as to provide for adjustment to conform to the size of the melon to be carried.

In connecting up the straps with a melon, 90 one of them will be wrapped about the melon at one side of the transverse center line thereof and the spurs or prongs 3 of it will be thrust into the melon. The same procedure will be repeated with the complementary strap on the opposite side of said transverse center line. This will bring the single hole 5 of each of the straps on what is for the time being the upper side of the melon, the row of holes 6 being opposite the 95 single hole 5 as shown for instance in Fig. 1.

The handle comprises a bail or yoke like body 7 from the end branches of which extend outwardly the flat feet 8, each of the feet having upstanding ears or lugs 9, the 105 shanks of which are at about right angles with the feet.

The following procedure may be adopted in connecting the article with a melon: Initially the handle will be laid upon the 110 upper side of the melon and the terminal lugs or ears 9 or those on the extreme limits

2
of the feet 8, as shown in Figure 8, will be thrust through the single perforations of hole 5 of each of the straps 2 after which the said straps will be wrapped about the 5 melon during which the prongs or spurs 3 will be thrust into the melon. The straps will then be brought round the melon and two of the holes 6 will then be positioned to receive the inner ears or lugs 9. This 10 operatively connects the handle with the straps 2 which at this time are rigidly associated with the melon.

What I claim is:—

A watermelon-carrier comprising two 15 strips to encircle the watermelon and provided with spurs for detachably connecting

the strips with said watermelon, the strips having a perforation at one end portion and a series of perforations at their opposite end portion, and a bail-like handle having 20 flat ends lying in a horizontal plane when the handle is in use, said ends being provided with upstanding lugs adjacent their edges which are adapted respectively to extend through end perforations in the strips 25 when the latter overlie said ends.

In testimony whereof I affix my signature.

SUMNER F. CALL.

In presence of—

ELIZABETH A. BANNING,
HEATH SUTHERLAND.
